TIMING MECHANISM

Leon F. Miller, Cleveland, and Robert W. Ellms,
Lakewood, Ohio, assignors to The Osborn
Manufacturing Company, Cleveland, Ohio, a
corporation of Ohio

Application April 26, 1935, Serial No. 18,393

3 Claims. (Cl. 121—164)

This invention is directed to a timing mold-making method and mechanism particularly adapted for use with fluid-pressure machinery, and especially intended to govern automatically the time of action of jolt machines and squeeze machines, whether separate or combined, for the making of sand molds in foundry work.

In the making of sand molds, it is customary to jolt the mold after filling in order to compact the sand and a common practice is also to squeeze the mold for the same purpose. Machinery is well known in the trade either for jolting, or for squeezing, and very frequently the two functions are combined in a single machine which is generally made with one cylinder for jolting and another for squeezing, the two cylinders being nested. Compressed air is almost universally used as a motive power for these mechanisms. Inasmuch as it is highly advantageous for the operator to keep his hands free to handle the molds, the supply of air to the machine either for jolting or for squeezing is usually controlled by a valve which the operator opens by knee pressure and holds open as long as he wishes the jolting or the squeezing, as the case may be, to continue.

The present invention is of a character to govern the supply of compressed air or other fluid pressure to such machinery so that all the operator need do is open the valve, whereafter the pressure will remain on for a predetermined period and then automatically shut itself off, thus controlling the number of jolting strokes or the time the squeeze is held.

The purposes of this invention include adding to the art a timing mechanism which will allow operation as indicated for a definite time and stop it at the end of that time, the timing mechanism being of a construction which is accurate, reliable, positive, compact, rugged, which can be easily and accurately regulated and which is relatively simple to manufacture.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In the accompanying drawings:

Fig. 1 is a partly diagrammatic elevation illustrating the piping and valve lay-out and the application of the timing mechanism;

Fig. 2 is a transverse vertical section through an automatic valve associated with the timing mechanism;

Fig. 3 is a longitudinal mid-section through the timing mechanism;

Fig. 4 is a section on the plane indicated at 4—4, Fig. 3; and

Fig. 5 is a section on the plane indicated at 5—5, Fig. 4.

The fluid for operating such mechanisms is usually compressed air, and this specification is accordingly written designating compressed air, although it will be understood that the apparatus is of general application with any fluid under pressure.

In the general lay-out, Fig. 1, the timing mechanism as a whole, indicated by the reference character 1, is shown as bolted or otherwise secured to part of the frame or cylinder 2 of a jolt or squeeze or jolt-squeeze machine, although for simplicity the invention will hereafter be referred to in its application to a jolt machine.

A valve 4 herein shown as having a knee-actuated operating lever 6 is illustrated as attached to another portion 2' of the machine conveniently accessible to the operator. Air reaches this valve through a branch 7 from an air main 10. Beyond the valve 4, the branch 7 is continued as at 7' to the valve cage 8 of the timer 1, and another branch, 9, runs from the timer to a diaphragm valve 11 on the air main 10. The diaphragm valve 11 controls flow of air to the jolt cylinder, being connected thereto by a continuation 10' of the main. Part of the piston P of the jolt or squeeze mechanism (as the case may be) is shown in Fig. 1. A cut-off valve 12, ordinarily left open, is illustrated as applied to the continuation 10'.

Before proceeding to the description of the timing mechanism, the operation of the valve 11, which is shown in detail in Fig. 2, will be explained as an aid to understanding the use of the timing mechanism.

The valve 11 comprises a two-piece casing, namely a body 13 and cover 14 having a flexible diaphragm 15 secured therebetween. A disk 16, carried by the upper side of the diaphragm, is downwardly urged by its own weight and by a spring 17. The valve body 13 includes an annular air chamber 18 into which the main 10 leads, and a central outlet 19 from which the continuation 10' goes to the jolt cylinder.

The valve cover 14 is hollowed, forming an air chamber 21 of somewhat irregular shape, and a central space receiving the spring 17 and a stem of the disk 16, the stem being within the spring.

Air under pressure is applied by the branch 9 to the upper surface of the diaphragm 15 and of the disk 16. The air chambers 18 and 21 are connected by a bleed passage 22, constantly open, which passage includes a perforation in the diaphragm 15.

When the branch 9 is closed, leakage of air through the bleed passage 22 builds up pressure in the upper chamber 21 with the result that when 10 the pressure in the upper and lower chambers 21 and 18 is equalized there is a greater area exposed to air pressure above the diaphragm than below it, so that the diaphragm descends. The descending action is also aided by the weight of 15 the disk 16 and the pressure of the spring 17. The diaphragm in descending seats on the top of the outlet 19, thus cutting off 18 from 19 and stopping flow of air through the main 10, 10'. Relief of pressure in the upper chamber 21 20 through opening the branch 9 by the timer, as described hereafter, allows the pressure beneath, in chamber 18, to raise the diaphragm, thus opening the main and supplying air to the jolt machine. It is thus apparent that the immediate 25 function of the timing mechanism in the illustrated preferred embodiment is to cause the opening or closing of the upper air chamber 21.

The timing mechanism per se is illustrated in Fig. 3 in its normal position, not under air pressure, ready but not operating. It comprises a cylinder 23 having the valve cage 8 secured to one side. A piston reciprocates in the cylinder and by its motion releases or sets a trigger mechanism protruding into the cylinder through a side opening 24. The cylinder 23 is closed and domed at the upper end by a cap 25 into one side of the top of which an air pipe 7", which is a continuation of 7', enters. The trigger mechanism actuates plunger valves 26 and 27 which open or close 30 the air branches 7' and 9. In Fig. 3 the valve 26 is open connecting the branch 7' through the pipe 7" to the cap 25, but there is no pressure above the piston, because the valve 4 is closed. A bleed valve 28, preferably a needle valve, is placed in the top of the cap. An intermediate 35 horizontal baffle 29 extends somewhat more than half way across the dome to protect the needle valve 28 from oil, dirt, moisture, and foreign matter generally, which would tend to clog it and 40 so stop the action of the timer or decrease its accuracy. A plug 30 closes the cylinder bottom. In the preferred form shown this plug is centrally 45 hollowed as at 31 to receive a spring 32, normally holding the piston in the upper position shown.

In the illustrative embodiment the piston is 50 double headed, the upper head 33 being thick and solid, and the lower head 34 thinner and perforated as at 35 for air escape. The two heads are connected by a sleeve 36 of less diameter, also 55 perforated, as at 37, for air escape. A leather packing 38 at the upper end of the piston is secured by the usual means such as a washer and cap screw. The space below the piston head 33 is vented to the atmosphere through the openings 35, 37, 24, and finally out through a passage 39, Fig. 4, in the upper part of the valve cage 8.

The valve cage 8 houses the trigger mechanism in its upper part and its lower part forms the body of both valves 26 and 27. Removable plugs 70 40 and a removable side plate 41 give access to the cage interior.

The trigger mechanism comprises the three-fingered rocker arm 42 pivoted at 43, and a latch 75 44 of roughly triangular outline pivoted near one angle of its short base to a pair of upstanding

fingers 45 of the rocker arm. The long forward finger 46 of the arm projects into the path of the lower piston head 34 and in down position bears against the top of the stem 47 of the valve 27, to open that valve. The rocker arm rear finger 48, much shorter, when down contacts the top of the stem 49 of the valve 26, thus opening the valve. A spring 51 thrusting upon the rear of the latch 44 below the pivot point, and seated in a recess in the side wall of the valve cage 8, urges 10 the latch 44 counterclockwise and the rocker arm 42 clockwise. The latch 44 is shouldered at 52 and at 53 to bear selectively against the valve cage wall at the top of the opening 24.

The inner tip of the latch 44 projects into the 15 path of the upper piston head 33. In the position of Fig. 3 the shoulder 52 holds the latch, and the spring 51 is compressed. The travel of the latch and of the rocker arm is between the full and dotted line positions, as will be described in 20 connection with the operation of the apparatus.

The details of the plunger valves 26 and 27 include the two stems 49 and 47 respectively, each suitably packed, each cone-shouldered at 54 to close on a conical seat 55. Each valve is guided 25 by an enlargement 56 fitting the lower part of the valve chamber, and is urged up from below by a spring 57.

The course of air through the valves is apparent from Fig. 4, the valve there shown being the outer 30 one, 26.

The operation of the mechanism is as follows:

Starting with the parts in the positions of the drawings, the jolt piston down, and a mold on the jolt table, the operator presses the knee valve 35 lever 6, thereby admitting air to the branch 7'. Inasmuch as the valve 26 is open, the air so admitted passes through the pipe 7" into the cap 25 thus moving the piston downward. Air will immediately begin to escape through the needle 40 valve 28 and bleed hole, but the rate of supply is substantially greater than the rate of escape. As the piston moves downward, the lower edge of the head 33 trips the latch 44 off its shoulder 52, whereupon the rocker arm and latch are 45 moved to the dotted line position of Fig. 3 by the spring 51, the reduced diameter of the sleeve 36 permitting such movement.

The finger 46 thus opens the inner valve 27, which in turn vents the branch 9 to the atmosphere, relieving the pressure in the upper chamber 21 of the diaphragm valve, Fig. 2, and so opening that valve and admitting air from the main 10 through the extension 10' to the jolt cylinder. The jolting continues so long as the diaphragm 55 valve remains open. The same movement of the rocker arm 42 to the dotted line position lifts the finger 48 from the stem 49, allowing the spring 57 to close the valve 26, thus stopping the supply 60 of air through the branch 7' and pipe 7" to the cylinder 23. With the air supply off, the pressure above the piston is relieved through the needle valve 28, allowing the piston to rise by the pressure of spring 32, the time of rising being regulated by the setting of the needle valve. 65

As the piston rises the lower head 34 pulls up the inner end of the finger 46, thus restoring the latch mechanism to the position of Fig. 3, allowing the valve 27 to close, and opening the valve 26. Thus the branch 9 is closed and air flow through 70 the bleed passage 22, Fig. 2, builds up pressure above the diaphragm, shutting the diaphragm valve and stopping the jolt action. At the same time the valve 26 is opened, but this by itself is not effective to start the jolt mechanism again be- 75

cause the valve 4 is now closed. The operator held his knee on the lever 6 only momentarily.

In using our timer for jolt-squeeze machines it is our preferred practice to use one timer for the 5 jolt air supply and another for the squeeze air supply.

Other modes of applying the principle of our invention may be employed instead of the one explained, change being made as regards the mechanism herein disclosed, provided the means stated 10 by any of the following claims or the equivalent of such stated means be employed.

We therefore particularly point out and distinctly claim as our invention:

15 1. In a pressure actuated timing mechanism, a piston operable by fluid pressure in one direction, means for returning said piston following release of fluid pressure, an air dome above said piston, an air supply connection to the air dome, a bleed 20 valve from said air dome, and a baffle within said air dome shielding said bleed valve while permitting flow of air thereto.

25 2. An automatic timing mechanism comprising a cylinder, a piston movable in one direction therein by fluid pressure, a spring in said cylinder adapted to be compressed by said piston movement and to move said piston in the reverse direction, a valve operating unit adjacent said cylinder, said unit comprising a lever adapted to 30 press selectively at opposite limits of its travel upon one only of two self-closing plunger valves,

a spring urging said lever to one limit of its travel, said lever protruding into the path of said piston and movable by said piston against the impulse of said spring to the other limit of its travel, admission of air to said piston being controlled by one of said plunger valves, and a bleed exhaust in said cylinder for compressed fluid above said piston.

3. An automatic timing mechanism comprising a cylinder, a piston movable in one direction 10 therein by fluid pressure, a spring in said cylinder adapted to be compressed by said piston movement and to move said piston in the reverse direction, a valve operating unit adjacent said cylinder, said unit comprising a lever adapted to 15 press selectively at opposite limits of its travel upon one only of two self-closing plunger valves, a spring urging said lever to one limit of its travel, said lever protruding into the path of an element of said piston and movable by said piston 20 against the impulse of said spring to the other limit of its travel, a trip finger protruding into the path of another element of said piston, said finger being adapted to hold said lever against the pressure of its spring during part of the 25 piston travel in one direction, admission of air to said piston being controlled by one of said plunger valves, and a bleed exhaust in said cylinder for compressed fluid above said piston.
